UNITED STATES PATENT OFFICE.

JOHN F. PACKER, OF CHICAGO, ILLINOIS, ASSIGNOR TO HIMSELF AND
J. HARLEY BRADLEY, OF SAME PLACE.

DESIGN FOR A RADIATOR.

SPECIFICATION forming part of Design No. 18,810, dated December 11, 1888.

Application filed October 27, 1888. Serial No. 289,345. Term of patent 14 years.

To all whom it may concern:

Be it known that I, JOHN F. PACKER, a citizen of the United States, residing at Chicago, in the county of Cook and State of Illinois, have invented and produced a new and original Design for Radiators for Steam or Hot-Water Heating Apparatus, of which the following is a specification, reference being had to the accompanying drawing, forming part thereof.

The figure is a front elevation of a radiator showing my design.

The leading feature of my design consists in a rectangular surface divided by ridges which extend diagonally across the rectangular surface, and also by ridges which extend horizontally across it, and provided with a post or upright on each side.

A A are the posts or uprights, which are cylindrical in form, and are located one on each side of the radiator.

B is the central portion included between the posts A. This central portion, B, as shown, is divided into four sections, which division of the portions B into sections forms no part of the design.

a are horizontal ridges which extend across the central portion, B, at right angles to the posts A.

b and c are ridges which extend across the several sections of the central portion at angles of about forty-five degrees to the uprights A A and at right angles to each other. The diagonal ridges b and c form inverted rectangular pyramids or frustums of pyramids in each section. The horizontal ridges a, in connection with the diagonal ridges b and c, form inverted frustums of triangular pyramids or triangular pyramids.

As shown, there are open spaces d between the several sections of the central portion, B; but these form no part of the design, the distinguishing features of which are the diagonal ridges and the horizontal ridges. The central portion thus divided into a number of figures in regular form presents a pleasing design.

What I claim is—

The design for a radiator herein shown and described, the same comprising the cylindrical posts or uprights A A and the central portion, B, divided by diagonal ridges b and c, as set forth.

JOHN F. PACKER.
